UNITED STATES PATENT OFFICE

ROBERT W. SPOFFORD, OF NEW YORK, N. Y.

ART OF COLORING RATTAN

No Drawing.

Application filed September 11, 1928. Serial No. 305,327.

This invention relates to the treatment of rattan and has for its object the coloring of the rattan which in some species comprises a core and a bark the latter being known by the natives as "bejucu" which surrounds the core of the rattan plant or vine.

Heretofore attempts have been made to color articles made of rattan but with indifferent success. Some articles of rattan furthermore are made by first peeling off the bark of the rattan plant in strips about three-eighths of an inch wide and these strips are sold in commerce under the name of "bejucu." The frame work of the article to be produced, usually some piece of furniture, is shaped as desired using the pliable rattan core from which the bejucu has been removed. If, for example, a chair is being constructed, the frame of the chair is made from the core and the bejucu is woven around this frame to form the seat, back, etc.

Applicant's problem was to find some way of coloring the rattan with a permanent coloring matter. The extremely hard enamel surface of the rattan would not hold paint or stain, as heretofore applied, neither of which would permeate the surface sufficiently to be permanently retained thereon. When the furniture article was stained or painted, the color was easily removed by ordinary use of the article and in a short time became defaced, with the result that manufacturers of rattan articles have ordinarily refrained from attempting to color artificially the manufactured article.

Manufacturers of rattan articles for a long time have attempted to treat the wood so as to render it permeable to paint or dye but no solvent has been found which would remove or soften its hard outer coating.

I have found that if the rattan, while in its commercial form, was immersed in a hot aniline dye bath and allowed to remain there for four hours to four days depending on the species, the hot bath would sufficiently soften the outer surface to allow the dye to penetrate it and remain permanently on the rattan. Furthermore, I discovered that due to the variable hardness of the outside enamel-like surface of the rattan, I obtained an un-

even penetration of the dye which resulted in each strip of the rattan having variegated hues and when these strips are woven together, the result was a beautiful blending of colors that could not be obtained in any other known way. The colors, moreover, would penetrate the enamel surface of the rattan sufficiently to resist the usual wear and the color of the furniture article would be preserved.

Many desired colored aniline dyes might be used and the effects obtained varied as desired. The variable hardness of the different parts of the rattan would cause variations in the finished color since more of the dye would sink in in some places than in others thus forming a most pleasing combination of colors when the rattan was worked up into the furniture article the colors of the rattan being different shades of the same foundation colored dye.

Articles of furniture made from rattan colored by my improved process, present a most pleasing appearance and the dye, having penetrated the enamel coating of the rattan, is permanent and will not wear off or fades as the stains and paints heretofore applied to rattan articles in the ordinary way have done.

I am aware that it has heretofore been proposed to treat the crude material of certain fibres such as jute, with various materials to color the fibres before weaving them into the finished article, but as far as I know, I am the first to discover that by immersing rattan in a hot bath having aniline dye therein, the dye would penetrate the enamel surface of the rattan to different depths and thus produce the variegated colors which would permanently resist the usual wear on the finished articles made from the materials so treated.

What I claim as new is:

1. The process of producing variegated permanent fast colors on rattan which consists in immersing the rattan in a hot bath of water with an aniline dye therein and allowing the same to remain in the dye until it has penetrated sufficiently to deposit the dye below and upon the surface of the outer por-

tion of the rattan to produce variegated colors in accordance with the texture of the wood being dyed.

2. The process of producing variegated permanent fast colors on rattan which consists in immersing the rattan in a hot bath of water with an aniline dye therein and allowing the same to remain in the dye for a period of time exceeding four hours until 10 it has penetrated sufficiently to deposit the dye below and upon the outer portion of the rattan to produce variegated colors in accordance with the texture of the wood being dyed.

15 3. As an article of manufacture, rattan strips colored variably with an aniline dye which has penetrated through the hard enamel surface of the rattan strips.

4. As an article of manufacture, rattan 20 strips colored in various shades of the same primary color of an aniline dye which has penetrated through the enamel surface of the rattan strips and extended therein different distances and deposited therein different 25 amounts of coloring matter to produce variegated shades of the same primary color on the strips.

In testimony whereof I hereunto affix my signature.
